Patented July 25, 1922.

FIG. 1.

FIG. 2.

FIG. 3.

Inventor:

Fletcher J. Scott

UNITED STATES PATENT OFFICE.

FLETCHER J. SCOTT, OF HURDLAND, MISSOURI.

SAWING MACHINE.

1,424,039.

Specification of Letters Patent. Patented July 25, 1922.

Application filed June 27, 1921. Serial No. 480,875.

To all whom it may concern:

Be it known that I, FLETCHER J. SCOTT, a citizen of the United States, residing at Hurdland, in the county of Knox, in the 5 State of Missouri, have invented a certain new and useful Improvement in Sawing Machines; and I do hereby declare the following to be a full, clear, and exact description of the invention, such as will enable others 10 skilled in the art to which it appertains to make and use the same.

This invention relates to a new and useful improvement in a cross-head for a sawing machine or for a coupling which may be inserted 15 in a connecting rod or pitman for a drag saw, and the principal object of this invention is to provide a means whereby the saw may be changed to cut in either a horizontal or a vertical plane, and means where- 20 by this may be easily and quickly accomplished.

In the accompanying drawings Fig. 1 is a perspective view of my improved device with the saw in position to cut in a vertical 25 plane. Fig. 2 is a view similar to Fig. 1 with the saw arranged to cut in a horizontal plane. Fig. 3 is a detail of the latch used to secure the pivoted member 6 in either of its two positions.

30 Referring more particularly to the drawing wherein like reference characters designate like parts, 1^a represents a guide bar rectangular in cross section upon which is mounted a coupling or cross-head 2^a capable 35 of being reciprocated thereon by means of a pitman or connecting rod 3^c, which may be connected to a crank or any other convenient reciprocating means. This pitman is pivotally mounted to the cross-head by a 40 pin 4.

Pivotally mounted on a pin 8 between two parallel guide bars on the cross-head is a member 6 provided with a rounded end as shown in the drawing, which provides a convenient handle therefor. This member also 45 contains two holes 9, one at each side of the pivot 8, into one of which one of the two latches 10 may enter to secure the bar 6, either in a vertical position, as shown in Fig. 50 1, or in a horizontal position, as shown in Fig. 2. The latch 10 is mounted through an

angular member 11, as clearly shown in Fig. 3, and provided with a spring 12 which tends to press the latch 10 into the groove in which the member 6 lies. This latch 10 is 55 provided in duplicate on the cross-head, one being provided on the horizontal guide strip across the top of the cross-head and the other being provided on the vertical guide strip, as clearly shown in Fig. 2. 60

Upon the pivoted member 6 is pivotally mounted as at 7 a saw carrying bar 5^c, which will turn with the member 6 to cause the saw to assume a position either in a horizontal or in a vertical plane. 65

It is apparent that the cross-head will reciprocate with a straight line motion and when it is desired to cut in a horizontal plane, as, for instance, in felling a tree, the member 6 will be placed as shown in Fig. 70 2 and held there by the latch 10 which is on the upper or horizontal guide of the cross-head, whereas when the tree is felled and it is desired to cut in a vertical plane, as to cut the tree into logs, it will merely be necessary to pull out the latch 10 holding the saw by the convenient and curved handle shown in Fig. 3 and lift the member 6 to vertical position, at the same time pulling out the latch 10 which is mounted on the vertical 75 guide strip and letting it seat in the hole 9 nearest the end remote from the handle of the member 6. 80

I claim:

1. A cross-head or guided means constituting a connection between a means for producing reciprocating motion, and a saw reciprocated thereby, and an element pivoted to said cross-head on an axis parallel to its reciprocating motion, to which element the 90 saw is attached. 85

2. A cross-head carrying a pivoted member, a saw carrying bar pivoted to said member and shiftable therewith to change the plane of the saw and means to retain the 95 said member in either of two positions at right angles to each other.

FLETCHER J. SCOTT.
